Elias B. Allen

United States Patent Office.

ELIAS B. ALLEN, OF PORTLAND, MAINE.

Letters Patent No. 67,476, dated August 6, 1867.

IMPROVEMENT IN PISTON-PACKING.

The Schedule referred to in these Letters Patent and making part of the same.

TO ALL WHOM IT MAY CONCERN:

Be it known that I, ELIAS B. ALLEN, of Portland, in the county of Cumberland, and State of Maine, have invented an Improved Piston-Pack; and I hereby declare the following to be a full, clear, and exact description thereof, which will enable others to make and use my invention, reference being had to the accompanying drawings, forming part of this specification, in which—

a is a side view broken out of the piston; *b* is a top plan of one form in which I contemplate the arrangement of my packing; *c* is a section of the same and of a portion of the piston; *d* is a section of another form in which I contemplate the application of my invention; *e* is an edge view intended to illustrate the arrangement of the rings as they appear from the exterior; *f* shows a section of the piston with one form of my packing introduced therein.

The object of my invention is the production of an improved piston-packing, which is expanded, as is the case with certain others, by the steam in the cylinder as the piston is worked. I am aware of the existence of several patents for a similar purpose, and do not claim metallic rings so arranged as to be expansible by the operation of the steam in the cylinder. The object of my invention and claim is to embrace a particular arrangement of the rings in the piston, which arrangement I will now proceed to describe.

With one form of my invention I use a solid piston, a portion of which is shown at *a*, having a channel for the reception of the rings, as is common, this channel being between the two parts *j* *k*. In the centre of this channel is the raised part *g*, leaving the two smaller grooves *h* *i* upon either side thereof. Upon the inner edges of the parts *j* *k* is seen the small groove *m* running entirely around the piston. *n* shows vertical slots in the faces of the parts *j* *k*, and conducting into the small grooves *m*. There are two methods in which I contemplate the application of the metallic rings to form my improved packing, but the parts of the piston which I have above described and designated are used in both. My invention consists furthermore of interior and outer curved pieces of metal constructed and arranged as follows: What I term the interior pieces have the back portion *o*, which nearly fills the space between the parts *j* and *k* of the piston, and rests against the raised portion *g*, as clearly shown in the figure designated *d*. From the centre of this part *o* projects the shoulder *p*, as shown in the same figure. Upon this shoulder, on the upper and lower sides thereof, are placed the pieces *q* *r*, the parts *q* *r* *p*, and *p* with its back *o*, loosely filling the groove in the piston between *j* and *k*. The parts represented by *q* *r* are so arranged as to break the joints of the inner pieces designated by *p* *o*. This is illustrated at *e* and *b*. To insure this a small pin is set into the part *p*, as indicated at *s*. The above-described arrangement of metal packing can be used with a solid piston, inasmuch as it can be placed between the parts *j* and *k*, as illustrated in the drawing. At *c* is shown an arrangement of the packing similar to that illustrated at *d*, with this difference, that the shoulder *p'*, which corresponds to the shoulder *p* in the other arrangement, has small grooves at *t*, and the parts *q'* *r'*, corresponding to *q* and *r* in the other arrangement, have small lips, which fit into the said grooves *t*. Unlike the arrangement illustrated at *d*, pressure, in an outward direction, when applied within the circle formed by the arrangement of the different parts, will not force them apart, they being held together by the parts *q'* *r'*, breaking the joints of the interior parts, or those designated by *p'* *o'*, and also by the fitting of the lips on *q'* *r'* into the grooves on the part *p'*. The lips on *q'* *r'* fit somewhat loosely into the grooves in the shoulder *p'* in order to allow of a freer expansion of the packing. This form last described differs from the one first described also in this, that the piston in which it is used must have a follower, inasmuch as the packing cannot be inserted in the channel of the solid piston shown at *a*.

The operation of my packing in both of the described forms is as follows: When the packing is placed in its proper position in the piston steam is first taken through the vertical slots *n*, thence into the small grooves *m*, thence behind the parts *o* or *o'* into the space *h* or *i*, where, by its expansive force, it expands the packing to the necessary extent to fill the cylinder. It is evident that the steam is taken upon one side of the piston at the upward and upon the other at the downward stroke, or, in other words, upon opposite sides of the small projections *g*. Disclaiming any previous arrangements of metallic piston-packing, I desire further to specify that in upright engines, where the stroke is vertical, the parts *j* *k* of the piston may be ground or turned off to a depth the same as the vertical slots in the said parts of the said piston shown in fig. *a*.

I do not claim a packing made by a ring inserted between the flanges of the head, which ring is narrower

than the groove, so that as the piston moves the ring moves from one to the other side of the channel, and being pressed outwardly by steam admitted from the cylinder into a close chamber in the piston-head through one or more openings leading out therefrom and into the groove, the steam in the close chamber acting as a spring. My invention differs from this, both in the construction of the outer and inner segments of the annular packing in each of the two forms hereinbefore specified and in the manner of admitting the steam behind the packing to expand the same. Furthermore, my invention differs from the patent of Nathan P. Stevens, No. 44,674, October 11, 1864, above recited, in the raised part *g* in the centre of the channel.

What I claim as my invention, and desire to secure by Letters Patent, is—

1. In combination with the part *g* of the piston, the arrangement of the segments constructed as illustrated at *p o*, and the segments as shown at *q r*, in the manner and for the purposes herein described.
2. In combination with the part *g* of the piston, the arrangement of the segments *p' o'*, having the channels *t* on the part *p'*, and the segments *q' r'*, having the lips to fit into the said channels *t*, in the manner and for the purposes described.

Witnesses.
